UNITED STATES PATENT OFFICE.

GAETANO FRICANO, OF BUFFALO, NEW YORK.

CALENDAR-CLOCK.

1,300,372.

Specification of Letters Patent. Patented Apr. 15, 1919.

Application filed July 12, 1917. Serial No. 180,209.

To all whom it may concern:

Be it known that I, GAETANO FRICANO, a citizen of the United States, residing at Buffalo, in the county of Erie and State of New York, have invented a new and useful Improvement in Calendar-Clocks, of which the following is a specification.

This invention relates to clocks of the kind adapted to indicate the day and month 10 of the year in addition to the time of day.

The objects of the invention are to produce a clock provided with a mechanism of improved construction for transmitting motion from the clock mechanism to the calendar mechanism; also to provide means of improved construction for preventing the winding of the clock from interfering with the calendar mechanism; also to provide a mechanism of improved construction for 15 transferring motion from the day wheel to the month wheel of the clock; also to provide mechanism of improved construction for moving the day wheel to its starting position on the first of each month; also to 20 provide means of improved construction to prevent rebound when the day wheel moves into its starting position; also to improve the construction of devices of this kind in other respects hereinafter specified.

30 In the accompanying drawings:—

Figure 1 is a face view of the dial of a calendar clock embodying the invention.

Fig. 2 is a face view of the day indicator detached from the clock.

35 Fig. 3 is a front elevation of the clock mechanism embodying the invention with the dial removed therefrom.

Fig. 4 is a side elevation thereof showing the dial and day indicator in section.

40 Fig. 5 is a fragmentary sectional front elevation thereof showing the parts of the calendar mechanism in the position which they occupy on the last day of a thirty-day month.

45 Fig. 6 is a similar view showing the parts in the position which they occupy just before the day wheel returns to its starting position.

Fig. 7 is a similar view showing the positions of the parts with the day wheel in the starting position.

Fig. 8 is a fragmentary sectional bottom plan of the calendar mechanism on line 8—8, Fig. 3.

55 Fig. 9 is a fragmentary vertical sectional

view on an enlarged scale on line 9—9, Fig. 8.

Fig. 10 is a fragmentary sectional view on an enlarged scale on line 10—10, Fig. 7, showing the stop mechanism for the day 60 wheel.

Fig. 11 is a side elevation of the month wheel detached from the clock mechanism.

Fig. 12 is a fragmentary perspective view thereof on an enlarged scale. 65

Fig. 13 is a perspective view on an enlarged scale of a portion of the day wheel.

Fig. 14 is a perspective view of the 70 detent lever of the day wheel detached from the clock mechanism.

Fig. 15 is a fragmentary view of the clock mechanism taken in the direction indicated by the arrow in Fig. 3. 75

Fig. 16 is a fragmentary sectional view on an enlarged scale on line 16—16, Fig. 3. 80 Figs. 17 and 18 are fragmentary sectional elevations on line 17—17, Fig. 16, showing parts of the day wheel actuating mechanism in different positions.

Fig. 19 is a front elevation of a calendar 80 clock having a month indicating mechanism of slightly modified construction.

Fig. 20 is a fragmentary sectional view thereof showing the detent wheel of the month indicating mechanism. 85

The calendar mechanism of the clock may be applied to a clock mechanism of any suitable construction, that shown comprising the usual frame 25 on which the gear train 26 of the clock mechanism is suitably mounted. 90 The gear train shown may be actuated by any suitable means, such for example as a spring 27 secured on a winding shaft 28 having the usual squared end 29 adapted to receive the clock winding key. The winding mechanism is provided with the usual ratchet wheel 30 and pawl 31 which permit the winding shaft to be turned in a direction for winding without interfering with the gear train 26. The clock mechanism 26 is connected with an hour hand 32 and a minute hand 33 adapted to move over the usual clock dial 34. Any other clock mechanism may be employed for imparting movement to the calendar mechanism. 100

Movement may be imparted to the calendar mechanism from any desired part of the clock mechanism. In the construction shown the calendar mechanism derives its movement from the winding shaft 28 on 110

which a driving gear 35 is mounted to rotate relatively to the winding shaft 28. The driving gear 35 of the calendar mechanism is actuated by means of a driving member 36 rigidly mounted on the winding shaft 28, preferably on the squared end 29 thereof, and having arms 37 extending between the spokes of the driving gear 35 so that the gear 35 will be driven by the rotation of the winding shaft but will have a limited movement on this shaft independently of the driving member 36. The driving gear 35 meshes with a pinion 40 of a day wheel actuating mechanism mounted on a pin or post 41 rigidly secured on the frame 25 of the clock mechanism. The pinion 40 and the gear 35 in the construction shown are so proportioned that the pinion 40 will rotate five times in twenty four hours and is provided with mechanism for actuating a day wheel 42 once a day. In order to accomplish this result the following mechanism is preferably employed.

A wheel or plate 45 is rigidly secured on the gear 40 and is provided with a spring tooth 46 rotatably mounted on a pin 47 secured on the plate 45 of the day wheel actuating mechanism. The spring tooth 46 in the construction shown is pivotally mounted on a sleeve 48 pivoted on the pin 47 and a plate or holder 49 for the spring tooth is secured on the sleeve 48 and is provided with a shoulder or stop 50 against which the spring tooth is yieldingly held by means of a spring 51. Rotation is imparted to the sleeve 48 by means of a Geneva movement including a notched or toothed wheel or disk 52 rigidly secured on the sleeve 48 and having a plurality of teeth or projections, the outer faces 53 of which are curved and which are spaced apart forming slots or notches in which a tooth 55 on a disk 56 mounted on the post 41 is adapted to engage. The curvature of the outer face of the disk 52 is substantially the same as the curvature of the disk 56 so that the toothed wheel 52 will be rotated through the distance of one tooth or projection for each revolution of the wheel or plate 45 about its pivot 41. The Geneva wheel 52 is provided with five projections so that the spring tooth 46 connected therewith is rotated once about the pivot 47 for every five revolutions of the pivot 47 about the pivot 41. The spring tooth 46 is so positioned on the wheel or plate 45 that it will only actuate the day wheel 42 when the tooth extends substantially radial with regard to the pivot 41 as shown in Fig. 5 and since the spring tooth 55 only occupies this position once in five times, the day wheel 42 will be actuated once per day. When the clock is being wound the driving gear 35 rotates with the winding shaft 28 of the clock mechanism and rotates the wheel or plate 45 and the mechanism mount-

ed thereon in a reverse direction, causing the spring tooth to swing relatively to the sleeve 48 against the action of the spring 51 and thus to ride over the teeth of the day wheel 42 without moving this wheel. By providing a certain amount of lost motion between the driving member 36 and the driving gear 35 no harm will result if the winding shaft 28 is permitted to move forwardly through a short distance during the winding of the clock, as will frequently occur before the pawl 31 of the winding mechanism moves into engagement with a tooth of the ratchet wheel 30.

The day wheel 42 shown in the drawings is pivoted to turn about the axis on which the day and hour hands revolve and is provided at its periphery with ratchet teeth adapted to be engaged by the spring tooth 46 of the day wheel actuating mechanism and with an arm 60 suitably connected to turn with the day wheel 42 and carrying an annular card or indicator 61 on which the days of the month are indicated, the card being so positioned that the days of the month will be visible one at a time through a hole or opening 62 in the dial of the clock. The day wheel is connected with one end of a coil spring 63, the other end of which is connected to an arm or fixed part 64 of the frame 25 of the clock mechanism, so that the spring 63 will tend to hold the day wheel in its starting position in which the numeral "1" of the indicator 61 will be visible through the opening 62 in the dial. The day wheel is moved forwardly through the distance of one tooth at a time by the spring finger 46 against the action of the spring 63 and the day wheel is held against returning to its starting position by means of a pawl or detent 67 pivoted at 68 on the frame of the clock mechanism and held by means of a spring 69 in a position in which a tooth 70 of the pawl will engage in the ratchet teeth of the day wheel 42.

The means for indicating the months on the clock and for returning the day wheel to its starting position at the end of each month are preferably constructed as follows:

The day wheel 42 is provided with four pins or projecting portions 75, 76, 77 and 78 which are adapted to engage with teeth or projections formed on a month wheel 80 pivotally mounted on a pin or shaft 81 suitably pivoted in the clock frame. The month wheel in the construction shown is provided with a hollow hub portion 83, Fig. 8, which is yieldingly connected by means of a spring 84 with a gear or toothed wheel 85 secured on the pin or pivot 81, the spring 84 being preferably coiled about the pivot 81 and connected at one end to a projection 87 of the hub 83 of the month wheel and secured at its other end to a post 88 secured on the

gear or toothed wheel 85, the projection 87 and pin 88 being so positioned as to form a stop for the month wheel, against which the projection 87 thereof is held by the spring 84. The gear or toothed wheel 85 of the month indicating mechanism is held against movement by means of a tooth or part 90 formed on the detent 67 and which is adapted to engage between the teeth of the gear or toothed wheel 85.

The month wheel 80 is provided with a plurality of teeth or projections which are arranged to engage with one or another of the pins 75, 76, 77, 78 of the day wheel 42, the pin 78 being adapted to engage a projection on the month wheel 80 corresponding to a 28-day month and the pins 77, 76 and 75 being adapted to engage projections on the month wheel corresponding respectively to a twenty-nine, a thirty, and a thirty-one day month. In the construction shown for this purpose the pins are made of gradually increasing length, the pin 78 being the shortest and the pin 75 being the longest. The shortest pin 78 engages teeth 92 of the month wheel which extend toward the day wheel. A tooth 93 on the month wheel extends toward the day wheel to a less extent than the teeth 92 so that the pin 77 will engage this tooth but the pin 78 will pass the projection or tooth 93 without engaging the same. Another set of teeth 94 is arranged to be engaged by the pin 76 and a set of teeth 95 is arranged to be engaged only by the pin 75 of the day wheel. The projections or teeth 92, 93, 94, 95 of the month wheel are arranged in proper order depending upon the months which they represent so that the month wheel may be actuated when the day wheel has been advanced through a number of teeth corresponding to the days of the month.

The month wheel is turned through the distance of one tooth by any one of the pins 75, 76, 77, 78, when the tooth engages a corresponding month tooth or projection of the month wheel, causing the month wheel 80 to turn the gear or toothed wheel 85 through the distance of one tooth. This is accomplished by so proportioning the members that the detent 67 will be moved out of the space between two of the teeth of the wheel 85, thus permitting the wheel 85 to turn through the distance of one tooth. This causes the detent to be moved into the position in which the tooth 70 thereof will be moved out of engagement with the ratchet teeth of the day wheel 42, as shown in Fig. 6. When in this position a tooth 98 of the detent 67 will engage a detent or latch 100, thus holding the pawl 67 out of engagement with the teeth of the month wheel and permitting the spring 63 to return the month wheel to its starting position. The detent 100 shown in the drawings is mounted on a

pin 101 secured on an arm or projection 102 of the frame of the clock, and is yieldingly pressed by means of a spring 103 against the pawl 67 so as to engage the tooth 98 thereof when the detent is raised out of engagement with the day wheel 42. The detent or latch 100 is preferably provided with an outwardly extending arm 104 which enters into a slot 105 in the projection or arm 102 of the frame, which limits the movement of the pawl about its pivot. The spring connection between the month wheel 80 and the toothed or gear wheel 85 makes it possible for the month wheel to be moved back by the pins or projections on the day wheel 80 when the same is returning to its initial position without interfering with the gear 85. After the pins or projections of the day wheel have passed the month wheel, the spring 84 returns the month wheel to its operative positions in which the stops 87 and 88 are in engagement.

The detent 100 is provided at its other end with a slotted or bifurcated portion 110 which extends into operative relation to a stop pin 111 secured on the day wheel 42 and into which the stop pin of the day wheel 42 is adapted to enter when the day wheel returns to its initial position. The detent 100 thus acts as a stop to hold the day wheel 95 in its initial position when the pawl 67 is out of engagement therewith. The pin 111 engaging the latch 100 swings the same about its pivot to a sufficient extent to withdraw the latch from engagement with the tooth 98 of the pawl 67, thus permitting the pawl to again move into engagement with the teeth of the day wheel 42.

In order to prevent the momentum of the day wheel 42 from causing the same to rebound after striking the detent 100 a spring or retaining member 114 is preferably provided having a notched or bent portion 115 into which the arm 104 of the detent 100 is adapted to enter when the same has been moved to the limit of its movement by the pin 111 and which yieldingly holds the pawl against movement out of this position and thus prevents rebound of the day wheel, Fig. 7. Other means for returning the day wheel to its starting position at the end of each month may be provided.

The gear or toothed wheel 85 preferably meshes with a pinion 120 mounted on a pivot 121 suitably journaled in the clock frame and provided at its outer end with a hand or pointer 122 which indicates the months on the dial of the clock, the hand 122 being adapted to complete a revolution once in a year and the month wheel 80 is adapted to complete a revolution once in four years in order to enable the clock to correctly register the 29th day of February once every four years.

In the operation of the clock, the driving 130

gear 35 causes the wheel or plate 45 to revolve, thus causing the spring tooth 46 to be moved about its pivot 47 by means of the Geneva mechanism shown. When the spring tooth 5 is extended outwardly from the axis 41 of the wheel 45, the tooth will engage the day wheel, causing the same to advance through the distance of one tooth. The pawl 67 holds the day wheel in advanced 10 position until one or another of the pins 75, 76, 77 or 78 engage the corresponding tooth or projection of the month wheel and move the month wheel about its pivot through the arc of one tooth. This movement of the 15 month wheel causes the gear 85 to move the pawl 67 out of engagement with the day wheel, the detent 100 holding the pawl in this position. The day wheel is then returned to the initial position by the spring 20 63 and in returning to its starting position, the day wheel engages the detent 100, releasing the pawl 67 which again moves into engagement with the day wheel 42.

A clock of modified and somewhat simplified construction is shown in Figs. 19 and 20 25 in which a month wheel 130 is employed which is similar in construction to the month wheel 80 but which has only twelve teeth corresponding to twelve months of the year 30 and which consequently does not provide for an extra day in February in every fourth year. The month wheel 130 is connected in the same manner as hereinbefore described to a toothed wheel 131 mounted to rotate about 35 the same axis as the wheel 130 and engaging a tooth or pin 132 of a pawl 133 corresponding to the pawl 67. In other respects this mechanism corresponds substantially with that shown in Figs. 1 to 18.

40 I claim as my invention:—

1. The combination of a clock mechanism, 45 of mechanism for indicating the day and month of the year, including a day wheel, means actuated by said clock mechanism for advancing said day wheel once a day, a pawl for holding said day wheel in the advanced positions, a month wheel actuated by said day wheel once a month, said month wheel actuating said pawl to move the same 50 out of operative relation to said day wheel, and means adapted to engage said pawl when the same has been moved out of operative relation to said day wheel for holding said pawl in inoperative position until 55 said day wheel returns to its initial position.

2. The combination with a clock mechanism, 60 of mechanism for indicating the day and month of a year including a day wheel, of means actuated by said clock mechanism for advancing said day wheel once a day, a month wheel actuated by said day wheel once a month, and means engaging said month and said day wheels for holding the same in the advanced positions, said means 65 being moved out of engagement with said

day wheel by said month wheel when said day wheel actuates said month wheel to permit the day wheel to be returned to its initial position.

3. The combination with a clock mechanism, 70 of mechanism for indicating the day and month of a year including a day wheel, of means actuated by said clock mechanism for advancing said day wheel once a day, a month wheel actuated by said day wheel once 75 a month, means engaging said month and said day wheels for holding the same in the advanced positions, said means being moved out of engagement with said day wheel by said month wheel when said day wheel actuates said month wheel to permit the day wheel to be returned to its initial position, and a detent for engaging said holding means to hold the same out of operative relation to said day wheel until said day wheel 85 returns to its initial position.

4. The combination with a clock mechanism, 90 of mechanism for indicating the day and month of a year including a day wheel, of means actuated by said clock mechanism for advancing said day wheel once a day, a month wheel actuated by said day wheel once a month, means engaging said month and said day wheels for holding the same 95 in the advanced positions, said means being moved out of engagement with said day wheel when said day wheel actuates said month wheel to permit the day wheel to be returned to its initial position, a detent for engaging said holding means to hold the same out of operative relation to said day wheel until said day wheel returns to its initial position, and means on said day wheel adapted to engage said detent when 100 said day wheel returns to its initial position to move said detent out of engagement with said holding means.

5. The combination with a clock mechanism, 110 of mechanism for indicating the day and month of a year including a day wheel, of means actuated by said clock mechanism for advancing said day wheel once a day, a month wheel actuated by said day wheel once a month, a pawl engaging said day wheel to hold the same in the advanced 115 positions, means actuated by said month wheel when the month wheel is advanced by said day wheel to move said pawl out of engagement with said day wheel, a detent engaging said pawl when moved out of 120 operative relation to said day wheel, and a part on said day wheel adapted to engage said detent to move the same out of holding engagement with said pawl, said detent acting as a stop for holding said day wheel 125 in its starting position.

6. The combination with a clock mechanism, 130 of mechanism for indicating the day and month of a year including a day wheel, of means actuated by said clock mechanism

for advancing said day wheel once a day, a month wheel actuated by said day wheel once a month, a pawl engaging said day wheel to hold the same in the advanced 5 positions, means actuated by said month wheel when the month wheel is advanced by said day wheel to move said pawl out of engagement with said day wheel, a detent engaging said pawl when moved out of 10 operative relation to said day wheel, said detent having a bifurcated portion extending into operative relation to said day wheel, and a part on said day wheel adapted to enter into said bifurcated portion of said 15 detent to move the same out of holding engagement with said pawl and to stop the return movement of said day wheel.

7. The combination with a clock mechanism, of mechanism for indicating the day 20 and month of a year including a day wheel, of means actuated by said clock mechanism for advancing said day wheel once a day, a month wheel actuated by said day wheel once a month, a pawl engaging said day 25 wheel to hold the same in the advanced positions, means actuated by said month wheel when the month wheel is advanced by said day wheel to move said pawl out of engagement with said day wheel, a 30 detent engaging said pawl when moved out of operative relation to said day wheel, said detent having a bifurcated portion extending into operative relation to said day wheel, a part on said day wheel adapted to enter 35 into said bifurcated portion of said detent to move the same out of holding engagement with said pawl and to stop the return movement of said day wheel, and means for yieldingly holding said detent in the position 40 to which it is moved by said part of the day wheel to prevent rebound of said day wheel.

8. The combination with a clock mechanism, of mechanism for indicating the day 45 and month of a year including a day wheel, of means actuated by said clock mechanism for advancing said day wheel once a day, a month wheel actuated by said day wheel once a month, a gear wheel pivoted to turn 50 about the axis of said month wheel, a pawl adapted to hold said day wheel in the advanced position and having a part engaging said gear wheel, a connection between said month wheel and said gear wheel permitting a limited movement of said month 55 wheel with regard to said gear wheel, and means actuated by said gear wheel when turned by said month wheel for moving said pawl out of operative relation to said day 60 wheel to permit the same to return to its initial position.

9. The combination with a clock mechanism, of mechanism for indicating the day and month of the year including a day 65 wheel, means actuated by said clock mecha-

nism for advancing said day wheel once a day through an interval corresponding to a day, a month wheel extending into operative relation to said day wheel, projecting portions on said day wheel extending to various 70 distances from said day wheel, corresponding projecting portions on said month wheel extending into various positions with regard to said month wheel, one of said projections being provided for each month, said projections of 75 the day wheel being positioned to engage the projections of the month wheel and being so positioned with regard to said day wheel as to engage said projections on the month wheel after said day wheel has been turned 80 through a distance corresponding to a definite number of days, and means for returning said day wheel to its starting position after the same has advanced said month wheel.

10. The combination with a clock mechanism, of mechanism for indicating the day and month of the year including a day wheel, means actuated by said clock mechanism for advancing said day wheel once a 90 day through an interval corresponding to a day, a month wheel, pins projecting outwardly from said day wheel, said pins varying in length, and projections on said month wheel extending into different positions with 95 regard to said day wheel, a projection being provided for each month, said projections being adapted to be engaged by one or another of said pins for advancing said month wheel, and means for moving said day wheel 100 into its starting position after the same has actuated said month wheel.

11. The combination with a clock having a winding shaft, of mechanism for indicating the day and month of the year including a 105 day wheel and a ratchet device rotated by said winding shaft to actuate said day wheel once a day when said shaft is turned to actuate the clock, said ratchet means being movable relatively to said day wheel without 110 actuating the same when said shaft is turned for winding the clock.

12. The combination with a clock having a winding shaft, of mechanism for indicating the day and month of the year including 115 a day wheel, a gear mounted on said winding shaft, a pinion driven by said gear, a tooth mounted on said pinion and adapted to advance said day wheel once a day, said tooth being adapted to be turned in the reverse direction without actuating said day wheel.

13. The combination with a clock having a winding shaft, of mechanism for indicating the day and month of the year including a day wheel, a gear mounted on said winding shaft, a pinion driven by said gear, a tooth mounted on said pinion and adapted to advance said day wheel once a day, said tooth being driven relatively to said pinion by means of a Geneva mechanism mounted 125 130

on said pinion which causes the tooth to be placed in a position to engage said day wheel once during a predetermined number of revolutions of said pinion.

14. The combination with a clock having a winding shaft, of mechanism for indicating the day and month of the year including a day wheel, a gear mounted on said winding shaft, a pinion driven by said gear, a tooth mounted on said pinion and adapted to advance said day wheel once a day, said tooth being adapted to be turned in the reverse direction without actuating said day wheel, and means for rotating said tooth relatively to said pinion so that the same moves into operative relation to said day wheel at intervals.

15. The combination with a clock mechanism, of mechanism for indicating the day and month of a year including a day wheel, of means actuated by said clock mechanism for advancing said day wheel once a day, a month wheel which is positively engaged by said day wheel once a month for advancing said month wheel, a pawl engaging said day wheel to hold the same in advanced positions said pawl having a part engaging said month wheel for causing the advance movement of the month wheel to move said pawl out of engagement with said day wheel to permit the day wheel to return to its initial position, and means on said day wheel for engaging said month wheel to advance the same.

16. The combination with a clock mechanism, of mechanism for indicating the day and month of a year including a day wheel, of means actuated by said clock mechanism for advancing said day wheel once a day, a month wheel actuated by positive engagement with said day wheel once a month and extending into operative relation to said day wheel, parts on said day wheel extending into different positions with regard to the same, projections on said month wheel, each projection corresponding to a month, said projections extending into different positions depending upon the number of days in the month represented by said projections, said parts on the day wheel being arranged in such relation to the projections of the month wheel as to engage said projections after the day wheel has been advanced through intervals corresponding to the number of days of the month represented by the projection on the month wheel which is to be actuated by the day wheel, and means for returning said day wheel to its initial position when a part of said day wheel has engaged the projection of the month wheel to advance the same.

Witness my hand this 10th day of July, 1917.

GAETANO FRICANO.
